UNITED STATES PATENT OFFICE.

STEPHEN M. GRISWOLD, OF BROOKLYN, NEW YORK.

DESIGN FOR AN EYEGLASS-HOLDER.

SPECIFICATION forming part of Design No. 15,172, dated July 29, 1884.

Application filed May 26, 1884. Term of patent thirty years.

To all whom it may concern:

Be it known that I, STEPHEN M. GRISWOLD, of Brooklyn, in the county of Kings and State of New York, have invented and produced a new and original Design for Eyeglass Holders, of which the following is a full, clear, and exact description.

Reference is to be had to the accompanying drawings, forming part of this specification, in which similar letters of reference indicate corresponding parts in both the figures.

Figure 1 is a front elevation of my newly-designed eyeglass-holder, and Fig. 2 is a side elevation of the same, these two views being deemed necessary to fully illustrate my design.

The leading feature of my design is the ornamental configuration of the base of the holder; and it furthermore consists in the configuration of the hook of the holder in connection with said base.

A indicates the base of the holder; B, the hook, and C the pin thereof. The base A, which presents a flat and laterally-spread facial appearance, is ornamented on each of its side edges with two prominent scallop or rounded projections, D D, one above the other, mounted by an upper or outer narrower central extension, D', the side edges of which are of a less prominent convex form. The lower scallop D on the one side edge of the base is ornamented at its middle with a perforation, E, which gives a hollow arched appearance to

said scallop. The hook B is facially of tapering form from its base to its point, and presents the appearance of a tapering divider of the two lower or inner scallops, D D.

By this design a very neat and ornamental appearance is given to the entire holder.

What I claim is—

1. The within-described design for the base of an eyeglass-holder, which consists in the ornamentation of each of its side edges with two prominent scallops, D D, one above the other, mounted centrally by a narrower extension, D', having its side edges of convex form of lesser prominence than the side scallops, as shown.

2. The within-described design for an eyeglass-holder, which consists in a flat or spread-out base ornamented on each of its side edges with duplicate prominent scallops D D, the inner and lower one of which is centrally ornamented by a perforation, E, and all of which are mounted by a central extension, D', having convex side edges of less prominence than the scallops, in combination with the hook B, of facially tapering form, and presenting the appearance of a divider of the two lower or inner scallops, D D, as shown.

STEPHEN M. GRISWOLD.
